SNOW SLED

William R. Gibson, Butte, Mont.

Filed Dec. 31, 1962, Ser. No. 72,992

Term of patent 14 years

(Cl. D34—15)

FIG. 4

FIG. 5

FIG. 1 is a perspective of the snow sled showing my new design;

FIG. 2 is a plan view of the snow sled;

FIG. 3 is a side elevation of the snow sled;

FIG. 4 is a bottom view of the snow sled; and

FIG. 5 is a front elevation of the snow sled.

I claim:

The ornamental design for a snow sled, as shown.
